US00D511893S

(12) United States Design Patent (10) Patent No.: US D511,893 S
Chou et al. (45) Date of Patent: * Nov. 29, 2005

(54) PACKAGE FOR CONTACT LENSES

(75) Inventors: Yu-Jan Chou, Taipei (TW); Ming Lee, Tu Cheng (TW)

(73) Assignee: St. Shine Optical Co., Ltd. (TW)

() Term: 14 Years

(21) Appl. No.: 29/204,757

(22) Filed: May 4, 2004

(51) LOC (8) Cl. 03-01

(52) U.S. Cl. D3/264; D3/263

(58) Field of Search D3/219, 263, 264, D3/265, 252; 206/5, 5.1, 6
